(57) **CLAIM**

The ornamental design for a package for laundry additive, as shown and described.

DESCRIPTION

FIG. 1 is a perspective view of a first embodiment of the package for laundry additive;

FIG. 2 is a front view of the package for laundry additive of FIG. 1;

FIG. 3 is a rear view of the package for laundry additive of FIG. 1;

FIG. 4 is a side view of the package for laundry additive of FIG. 1;

FIG. 5 is a side view of the package for laundry additive of FIG. 1, opposite the side view shown in FIG. 4;

FIG. 6 is a top view of the package for laundry additive of FIG. 1;

FIG. 7 is a bottom view of the package for laundry additive of FIG. 1;

FIG. 8 is a perspective view of a second embodiment of the package for laundry additive;

FIG. 9 is a front view of the package for laundry additive of FIG. 8;

FIG. 10 is a rear view of the package for laundry additive of FIG. 8;

FIG. 11 is a side view of the package for laundry additive of FIG. 8;

FIG. 12 is a side view of the package for laundry additive of FIG. 8, opposite the side view shown in FIG. 11;

FIG. 13 is a top view of the package for laundry additive of FIG. 8;

FIG. 14 is a bottom view of the package for laundry additive of FIG. 8;

FIG. 15 is a perspective view of a third embodiment of the package for laundry additive;

FIG. 16 is a front view of the package for laundry additive of FIG. 15;

FIG. 17 is a rear view of the package for laundry additive of FIG. 15;

FIG. 18 is a side view of the package for laundry additive of FIG. 15;
FIG. 19 is a side view of the package for laundry additive of FIG. 15, opposite the side view shown in FIG. 18;
FIG. 20 is a top view of the package for laundry additive of FIG. 15;
FIG. 21 is a bottom view of the package for laundry additive of FIG. 15;
FIG. 22 is a perspective view of a fourth embodiment of the package for laundry additive;
FIG. 23 is a front view of the package for laundry additive of FIG. 22;
FIG. 24 is a rear view of the package for laundry additive of FIG. 22;
FIG. 25 is a side view of the package for laundry additive of FIG. 22;
FIG. 26 is a side view of the package for laundry additive of FIG. 22, opposite the side view shown in FIG. 25;
FIG. 27 is a top view of the package for laundry additive of FIG. 22;
FIG. 28 is a bottom view of the package for laundry additive of FIG. 22;
FIG. 29 is a perspective view of a fifth embodiment of the package for laundry additive;
FIG. 30 is a front view of the package for laundry additive of FIG. 29;
FIG. 31 is a rear view of the package for laundry additive of FIG. 29;
FIG. 32 is a side view of the package for laundry additive of FIG. 29;
FIG. 33 is a side view of the package for laundry additive of FIG. 29, opposite the side view shown in FIG. 32;
FIG. 34 is a top view of the package for laundry additive of FIG. 29;
FIG. 35 is a bottom view of the package for laundry additive of FIG. 29;
FIG. 36 is a perspective view of a sixth embodiment of the package for laundry additive;
FIG. 37 is a front view of the package for laundry additive of FIG. 36;
FIG. 38 is a rear view of the package for laundry additive of FIG. 36;

FIG. 39 is a side view of the package for laundry additive of FIG. 36;
FIG. 40 is a side view of the package for laundry additive of FIG. 36, opposite the side view shown in FIG. 39;
FIG. 41 is a top view of the package for laundry additive of FIG. 36;
FIG. 42 is a bottom view of the package for laundry additive of FIG. 36;
FIG. 43 is a perspective view of a seventh embodiment of the package for laundry additive;
FIG. 44 is a front view of the package for laundry additive of FIG. 43;
FIG. 45 is a rear view of the package for laundry additive of FIG. 43;
FIG. 46 is a side view of the package for laundry additive of FIG. 43;
FIG. 47 is a side view of the package for laundry additive of FIG. 43, opposite the side view shown in FIG. 46;
FIG. 48 is a top view of the package for laundry additive of FIG. 43;
FIG. 49 is a bottom view of the package for laundry additive of FIG. 43;
FIG. 50 is a perspective view of an eighth embodiment of the package for laundry additive;
FIG. 51 is a front view of the package for laundry additive of FIG. 50;
FIG. 52 is a rear view of the package for laundry additive of FIG. 50;
FIG. 53 is a side view of the package for laundry additive of FIG. 50;
FIG. 54 is a side view of the package for laundry additive of FIG. 50, opposite the side view shown in FIG. 53;
FIG. 55 is a top view of the package for laundry additive of FIG. 50; and,
FIG. 56 is a bottom view of the package for laundry additive of FIG. 50.
The broken lines shown are included for the purpose of illustrating the unclaimed portions of the article and form no part of the claim.
